Primary Examiner — Jae Liang*Assistant Examiner* — Samantha Lynne Brodowski(74) *Attorney, Agent, or Firm* — ScienBiziP, P.C.(57) **CLAIM**

The ornamental design for a protective case as shown and described.

DESCRIPTION

FIG. 1 is a front, left and top perspective view of a protective case showing my new design.

FIG. 2 is a rear, right and bottom perspective view of a protective case showing my new design.

FIG. 3 is a front elevation view thereof.

FIG. 4 is a rear elevation view thereof.

FIG. 5 is a left-side elevation view thereof.

FIG. 6 is a right-side elevation view thereof.

FIG. 7 is a top plan view thereof; and,

FIG. 8 is a bottom plan view thereof.

The broken lines are included for the purposes of illustrating portions of the protective case that form no part of the claimed design.

1 Claim, 8 Drawing Sheets(56)
